UNITED STATES PATENT OFFICE.

CARLYLE J. SHERWOOD, OF SAN FRANCISCO, CALIFORNIA, ASSIGNOR TO COEN CO., OF SAN FRANCISCO, CALIFORNIA, A CORPORATION OF CALIFORNIA.

BURNER.

Application filed September 10, 1919. Serial No. 322,938.

To all whom it may concern:

Be it known that I, CARLYLE J. SHERWOOD, a citizen of the United States, residing at the city and county of San Francisco and State of California, have invented new and useful Improvements in Burners, of which the following is a specification.

This invention relates to an oil burner, and especially to means for automatically 10 varying the size of the fire or the quantity of fuel burned.

There are many small plants and isolated boiler installations, for instance, in the oil field, mines, factories, etc., which employ 15 oil burners. Comparatively little attention is given such installations with regard to fuel economy as the elaborate automatically-controlled devices of various makes employed in larger plants for the purpose of 20 maintaining a steady steam pressure under variable load are prohibitive in cost when considering small installations.

One of the objects of the present invention is to provide a steam atomizing fuel 25 burner employing oil or the like which is suitable either for large or small installations and which is provided with means in the burner proper actuated either by the oil or atomizing agent under pressure, or both, for automatically varying the size of the 30 fires or the quantity of fuel burned, thereby eliminating the necessity of employing automatic controlling devices such as thermostats, pressure reducing valves, etc. and 35 other extra attachments now employed in the larger plants, and, furthermore, permitting economical fuel regulation whether it be in large or small installations.

Another object of the invention is to provide a manual control whereby the quantity 40 of fuel or atomizing agent employed may be regulated independent of each other or in unison.

Further objects will hereinafter appear.

The invention consists of the parts and the 45 construction, combination and arrangement of parts as hereinafter more fully described and claimed, having reference to the accompanying drawings, in which—

Fig. 1 is a central, vertical, longitudinal 50 section through the burner and the automatic mechanism whereby it is actuated.

Fig. 2 is a cross section on the line 2—2 of Fig. 1.

Fig. 3 is a cross section on the line 3—3 of Fig. 1.

Fig. 4 is a front view of the burner nozzle. Referring to the drawings in detail and particularly to Fig. 1, A indicates a casing which is provided with two intake openings, 55 one for oil, as indicated at 2, and one for steam, as indicated at 3. The opening 3 communicates with a chamber 12 and the opening 2 with a chamber 2', said chambers being formed within the casing A as shown. Secured to the forward end of the casing or 60 screwed into the same, as shown at 4, is a pipe 5 on the outer end of which is secured a burner nozzle 6 of suitable construction. Slidably mounted interior of the nozzle 6 is 65 a valve 7, in the outer surface of which is formed a series of tapering grooves or slots 8. The valve 7 is secured to the thread end of a corrugated expansible tube 9, the opposite end of which is secured within a central 70 nipple 10, said nipple being threaded into the wall of chamber 12.

The oil inlet supplying connection 2 through the chamber 2' communicates with the pipe 5 or an annular passage 11 formed 75 exterior of the corrugated expansible tube while the steam supplying connection 3 communicates through the chamber 12 with the interior of the corrugated tube or annular passage 14 formed within the tube. Positioned 80 centrally of the tube and extending longitudinally through the same is a valve stem 15. The forward end of this stem passes through the valve 7 and grooves 16 somewhat similar to those shown at 8 are 85 formed in the stem, these grooves serving the function of regulating the volume of atomizing steam employed, as will hereinafter be described, while the grooves 8 serve 90 the function of regulating the quantity of oil or fuel consumed. The opposite end of the stem 15 extends through the central chamber 12 and a stuffing box 17, while the 95 extreme outer end or the portion exterior of the stuffing box passes through a nut 18. The nut proper is turnably mounted in a bracket extension 19 formed on the casing A and it may be locked against turning movement by means of a lock nut 20. The nut 18 is threaded exteriorly for the reception of 100 the lock nut 20 and interiorly to engage threads 21 formed on the stem. The stem is otherwise provided with a handle 22, the

105

function of which will hereinafter be described.

The corrugations formed in the expansible tube are thread-like in formation and the purpose of employing an expansible tube as shown is to provide means for automatically regulating the discharge of oil and steam through the valve 7, that is, variations in pressure either in steam or oil, or in both, when passing through the annular passages 11 and 14 will cause extension or contraction of the expansible tube, by the force which it exerts against the corrugated sides of the tube, plus the pressure against the valve 7 and thereby moving the valve 7 and consequently regulating the discharge of steam and oil passing through the burner nozzle 6.

For the purpose of regulating the expansible action of the tube 9, I provide a key 23. This key is carried by the stem 15 and is in reality nothing more or less than the plate (see Figs. 1 and 2) which passes through a slot 24 formed in the stem 15, the outer ends of the plate being provided with threadlike projections to engage the thread-like corrugations formed in the tube. The pitch existing between the threads formed by the corrugated tube 9 and threaded key 23 is equal to the pitch of threads between the stem 15 and nut 18.

The plate or key 23 may be turned in unison with the stem or its position may be advanced or retracted within the tube; and it may be advanced or retracted in unison with the stem 15 without turning the stem if it is desired to adjust the position of the valve 7 with relation to the nozzle 6, and thus, increase or decrease the port area formed between the nozzle and the grooves 8.

In actual operation, it can be seen that I have provided an atomizing burner capable of handling oil or similar fuel, and, further, that I have provided means for automatically regulating the discharge of the fuel and for manually regulating the discharge of fuel. Similarly, that an atomizing agent may be employed and that the volume or quantity employed may be automatically or manually controlled. This is accomplished in the following manner: With the burner disposed at the entrance of a furnace box under a boiler, it is obvious that the burner is connected with a source of oil supply under pressure, as a pump not here shown; similarly, that the atomizing agent or steam employed will be supplied by a pipe 3^a directly connected with the boiler. When oil and steam are delivered to the burner, it can be seen that the oil will escape through the annular passage 11, the channels 8 and the atomizing nozzle 6. Similarly, that the steam admitted will escape through the central chamber 12, the annular passage 14, the grooves 16 and the nozzle 6, the atomizing effect being obtained when the steam and

oil meet within the nozzle and discharge through the opening 6^a formed therein.

Any variation in steam or oil pressure will have a certain effect on the expansible tube 9, that is, the valve 7 serves as a partial closure for the pipe 5 and the expansible tube 9, and it is therefore obvious that variation in pressure will tend to expand or contract the tube 9 as before described, thereby imparting a movement to the valve 7 which will automatically vary the flow of steam and oil through the nozzle. Any increase in pressure will cause extension of the tube and forward movement of the valve. The ports formed between the grooves 8 and the nozzle will thereby be reduced in area and similarly the ports formed between the grooves 16 and the forward end of the valve will be reduced. A decrease in pressure of oil or steam will permit partial contraction of the tube and thereby retraction of the valve which increases the areas referred to and consequently the volume or quantity of steam and oil discharged.

The position of the valve 7, in Fig. 1, is such that extreme inward movement to the left has been reached. The grooves 8 formed in the valve are shallow at their inner ends and taper angularly outward. Conversely, grooves 16 are shallow at their outer ends and have their largest area and depth at their inner ends.

For purposes of explanation it might be stated that the admission of steam to the inner ends of the grooves 16 may be considered as constant, and if such is the case the discharge of steam will then be controlled by the area presented at the outer ends of the grooves. For instance if valve 7 moves forwardly or to the right, see Fig. 1, the discharge area at the outer ends of the grooves 16 will decrease and hence the flow of steam will be lessened. The discharge of oil will also be less as the shallow inner ends of the grooves 8 will decrease in area and therefore decrease the amount of oil discharged. Again, if the movement of the valve 7 is to the left, the area of the grooves 8 will increase at the inner end and a larger quantity of oil will discharge. The area presented by the outer ends of the grooves 16 will similarly increase and the volume of steam discharging will increase.

From the foregoing description it should be apparent that positive automatic regulation of the fuel and the atomizing agent employed is therefore obtained without resorting to the use of thermostats, pressure-reducing valves, etc. and other attachments such as are employed in the larger plants. As the device here shown is simple and compact in construction and cheap to manufacture, it may be employed in small and isolated plants without excessive cost.

While the automatic regulation referred to may be looked upon as the most important

feature of the invention, it is obvious that hand regulation is desirable. Such regulation is easily obtained in the present instance, and is accomplished by either turning the 5 stem or by moving it bodily in a longitudinal direction. If it is desired to turn the stem 15, it is merely necessary to turn the handle 22. The stem may then be retracted or projected with relation to the valve 7 depending upon the direction in which the stem is turned. The quantity of steam or atomizing agent employed may, therefore, be regulated without disturbing the oil flow. Again, if it is desired to increase or decrease 10 the quantity of oil discharged, it is merely necessary to slightly unscrew the lock nut 20 and turn the nut 18 while holding the handle 22 stationary. The tension of the tube 9 existing between the key 23 and 15 nipple 10 has a tendency to always draw the stem 15 forwardly and therefore the shoulder of the nut 18 is continuously drawn against the bracket 19. For this reason when the nut 18 is turned and the handle 22 held stationary, the stem 15 must be retracted or projected depending upon the direction in which the nut 18 is turned. The 20 bodily movement of the stem 15 will likewise draw the key 23 which in turn through 25 the tube 9 will likewise move the valve 7 with relation to the nozzle 6, thereby decreasing or increasing the area formed between the nozzle and grooves 8, and consequently increasing and decreasing the quantity 30 of oil discharged without increasing or decreasing the flow of the atomizing agent. It can, therefore, be seen that means are provided for manually increasing and decreasing the flow of the atomizing agent or 35 for manually increasing or decreasing the flow of the fuel discharge and that these regulations may be obtained independently of each other. Again, it is possible to increase or decrease the flow of the atomizing agent and fuel employed in unison either by 40 automatic action or by manual operation, the automatic action being obtained by the expandable action of the tube 9 and the manual operation by turning the handle 22 and the nut 18 in unison, such movement 45 permitting retraction or projection of the valve and the stem in unison.

While the foregoing description describes the invention in combination with a fuel 50 burner, I wish it understood that the automatic and manual control here produced may be used for various purposes, for instance, in the governing of fuel and oil pumps, water pumps, steam engines, turbines, etc. or it can be generally applied for the automatic and manual regulation of the flow of any fluid relative to changes in pressure of that fluid or changes in pressure in one or two separately supplied liquids or 55 fluids.

A burner as here shown will supply the needs of either small or large boiler installations and should materially increase the economy of fuel employed and insure a steady boiler pressure under variable load 70 as the operation of the burner will be entirely automatic once installed.

Another important feature of the present invention is the thread-like formation of the corrugations in the expandable tube and the 75 key within the tube engaging the thread-like corrugations. By referring to Fig. 1 it will be seen that the key is secured in the stem and is therefore turnable in unison with the stem within the tube, or it may be bodily 80 advanced or retracted in unison with the stem. This last named is of great importance as it provides a means whereby the expandable action of the tube may be adjusted. By providing this means it is possible 85 to regulate the burner so that it is equally sensitive and automatic in action, whether operating under fluid pressures of 60 pounds or 150 pounds, that is, if the burner is operated under a comparatively low pressure, say, 60 pounds, it is obvious that a more sensitive expandable member is required under such conditions. The key will therefore assume a position adjacent the fixed 90 end of the expandable tube. If the fluid is delivered to the burner under high pressures, say 150 pounds or more, it is obvious that the expandable action of the tube must be decreased, as the movement would otherwise be too great. It is therefore only necessary 95 to advance the key with relation to the tube so that it will assume a position closer to the valve whereby the fluid flow is regulated. In other words, a shorter section of tubing is depended upon for automatic regulation 100 when operating under high pressures and a longer section of the tube is employed when working under lower pressures.

While the apparatus here shown is more or less specific in construction, I wish it understood that various changes in the form, proportion and general details of design may be resorted to within the scope of the appended claims. Similarly, the materials and finish of the several parts employed may 110 be such as the experience and judgment of the manufacturer may dictate or varying conditions may demand.

Having thus described my invention, what I claim and desire to secure by Letters 120 Patent is:

1. An automatic fluid flow regulator comprising a casing, said casing having two separate chambers formed therein, means for admitting a fluid under pressure to one chamber, means for admitting another fluid under pressure to the other chamber, a discharge pipe communicating with one chamber, a discharge nozzle on said pipe, an expandable tube connected with the walls of 125

130

second-named chamber at its one end and its other end extending to the discharge nozzle, said tube adapted to be expanded or contracted with variation in pressure of both 5 or either fluid, and a valve actuated by said expanding and contracting movement adapted to regulate the discharge of both fluids.

2. An automatic fluid flow regulator comprising a casing, said casing having two 10 separate chambers formed therein, means for admitting a fluid under pressure to one chamber, means for admitting another fluid under pressure to the other chamber, a discharge pipe communicating with one chamber, a discharge nozzle on said pipe, an expandable tube connected with the second-named chamber and with the discharge nozzle, said tube adapted to be expanded or contracted with variation in pressure of both 15 or either fluid, a valve actuated by said expanding and contracting movement adapted to regulate the discharge of both fluids, and manually actuated means for adjusting the position of the valve independent 20 of the expandable tube to increase or decrease the discharge of either fluid independent of the other.

3. An automatic fluid flow regulator comprising a casing having two separate chambers formed therein, means for admitting a fluid under pressure in one chamber, means for admitting fluid under pressure to the other chamber, a discharge pipe connected with the first-named chamber, a discharge 35 nozzle on said pipe, a corrugated expandable tube within the discharge pipe communicating with the second-named chamber, said tube adapted to be expanded or contracted with variations in pressure of either or 40 both fluids, and a valve attached to said tube adapted to automatically regulate the discharge of the fluids.

4. An automatic fluid flow regulator comprising a casing having two separate chambers formed therein, means for admitting a fluid under pressure to one chamber, means for admitting fluid under pressure to the other chamber, a discharge pipe connected with the first-named chamber, a discharge 45 nozzle on said pipe, a corrugated expandable tube within the discharge pipe communicating with the second-named chamber, said tube adapted to be expanded or contracted with variations in pressure of either or both 50 fluids, a valve attached to said tube adapted to automatically regulate the discharge of the fluids, and manually-actuated means operable independent of the expandable tube for adjusting the position of the valve to increase or decrease the discharge of either 55 fluid or both.

5. An automatic fluid flow regulator comprising a casing having two separate chambers formed therein, means for admitting a fluid under pressure to one chamber, means 60

for admitting a fluid under pressure to the other chamber, a discharge pipe connected with the first-named chamber, a discharge nozzle on said pipe, a corrugated expandable tube within the discharge pipe communicating with the second-named chamber, said tube adapted to be expanded or contracted with variations in pressure of either or both fluids, a valve attached to said tube adapted to automatically regulate the discharge of the fluids, a stem extending longitudinally through the casing, the expandable tube and the valve, and manually actuated means for moving the stem and valve longitudinally and for turning the stem to advance or retract the same with relation to the valve.

6. An automatic fluid flow regulator comprising a casing having two separate chambers formed therein, a discharge pipe connected with one of said chambers, a discharge nozzle on the end of said pipe, means for admitting a fluid under pressure to the first-named chamber, means for admitting a fluid under pressure to the second-named chamber, a valve having a central passage formed therein and a series of grooves on its outer surface, said valve co-operating with the nozzle, means for conveying the fluid under pressure delivered to the second-named chamber and discharging the same through the central passage in the valve, means in said passage for regulating the discharge of the second-named fluid, said means comprising a rod extending longitudinally through the casing, the discharge pipe and the valve, and a series of grooves formed in the outer end of the stem and communicating with the central passage formed in the valve.

7. An automatic fluid flow regulator comprising a casing, means for admitting a fluid under pressure, a discharge pipe, a discharge nozzle for the escape of the fluid, a valve having a series of grooves formed in its outer surface co-operating with the nozzle to regulate the discharge of the fluid, an expandable tube in the casing and in the discharge pipe adapted to be expanded or contracted by variations in the fluid pressure and means for transmitting said expanding or contracting movement of the tube to automatically regulate the position of the valve.

8. An automatic fluid flow regulator comprising a casing, means for admitting a fluid under pressure, a discharge pipe, a discharge nozzle for the escape of the fluid, a valve having a series of grooves formed in its outer surface co-operating with the nozzle to regulate the discharge of the fluid, an expandable tube in the casing and in the discharge pipe adapted to be expanded or contracted by variations in the fluid pressure, said tube being rigidly secured at one end and secured to the valve at the opposite end.

to automatically change the position of the valve and manually actuated means for contracting or extending the tube to adjust the position of the valve independent of the 5 automatic extension or contraction of the tube.

9. An automatic fluid flow regulator comprising a casing, means for admitting a fluid under pressure, a discharge pipe, a discharge 10 nozzle for the escape of the fluid, a valve having a series of grooves formed in its outer surface co-operating with the nozzle to regulate the discharge of the fluid, an expansible tube in the casing and in the discharge 15 pipe adapted to be expanded or contracted by variations in the fluid pressure, said tube being rigidly secured at one end and secured to the valve at the opposite end to automatically change the position of the 20 valve, means for admitting a second fluid under pressure, a central opening formed in the valve through which said second fluid is adapted to discharge, said second-named fluid passing through the expansible tube 25 when discharging, and means actuated by the expanding and contracting action of the tube for automatically regulating the discharge of the second-named fluid.

10. An automatic fluid flow regulator comprising a casing, means for admitting a fluid under pressure, a discharge pipe, a discharge nozzle for the escape of the fluid, a valve having a series of grooves formed in its outer surface co-operating with the nozzle 30 to regulate the discharge of the fluid, an expansible tube in the casing and in the discharge pipe adapted to be expanded or contracted by variations in the fluid pressure, said tube being rigidly secured at one end and secured to the valve at the opposite end to automatically change the position of the valve, means for admitting a second fluid under pressure, a central opening formed in the valve through which said second fluid is adapted to discharge, said second-named fluid passing through the expansible tube 35 when discharging, and means actuated by the expanding and contracting action of the tube for automatically regulating the discharge of the second-named fluid.

11. An automatic fluid flow regulator comprising a casing, means for admitting a fluid

under pressure, a discharge pipe, a discharge 60 nozzle for the escape of the fluid, a valve having a series of grooves formed in its outer surface co-operating with the nozzle to regulate the discharge, an expansible tube adapted to be expanded or contracted 65 by variations in the fluid pressure, said tube being rigidly secured at one end and secured to the valve at the opposite end to automatically change the position of the valve, means for admitting a second fluid under pressure, 70 a central opening formed in the valve through which said second fluid is adapted to discharge, said second-named fluid passing through the expansible tube when discharging, a rod extending longitudinally 75 through the casing, the expansible tube and the central passage in the valve, grooves formed in the rod, said grooves extending through the central passage in the valve for the escape of the second-named fluid, and 80 manually actuated means for retracting the rod, the tube and the valve, or for projecting the same with relation to the nozzle, said means also adapted to project or retract the rod independently of the tube and valve. 85

12. An automatic fluid flow regulator comprising a casing having an outlet opening formed therein, means for admitting the fluid under pressure, a valve adapted to regulate the discharge of fluid through the outlet opening, a corrugated expansible tube in the casing, said tube having corrugations of thread-like formation, means for rigidly securing the tube at one end, means securing the opposite end of the tube to the valve, a 90 rod entering the tube, a threaded key on the rod engaging the thread-like corrugations in the tube, and means for securing the rod and key against movement, and varying the expansible length of the tube. 95

13. In a device of the character described, a casing, a corrugated tube within said casing, means for securing one end of the tube, means for delivering a liquid under pressure to the interior of the tube, and means for delivering a separate liquid under pressure to the casing, and a valve member secured to the end of the tube operable for simultaneously decreasing or increasing the flow of a liquid from the tube and casing. 100

In testimony whereof I have hereunto set my hand in the presence of two subscribing witnesses.
